UNITED STATES PATENT OFFICE.

MICHAEL J. OWENS, DECEASED, LATE OF TOLEDO, OHIO; BY HAZEL O. BEESCH, JAMES C. BLAIR, AND JOHN H. MCNERNEY, ADMINISTRATORS, OF TOLEDO, OHIO, ASSIGNEES TO THE OWENS BOTTLE COMPANY, OF TOLEDO, OHIO, A CORPORATION OF OHIO.

FURNACE.

Application filed September 20, 1924. Serial No. 738,778.

The present invention relates to furnaces of the type in which the raw materials are melted and a high temperature maintained by burning a mixture of air and fuel gas within the furnace. The primary object of the invention is to provide practical and reliable means for maintaining a uniform temperature within the furnace and avoiding waste of fuel gas.

10 The invention is herein shown in connection with a glass melting tank furnace. In such furnaces, it is customary to admit fuel gas and atmospheric air in suitable proportions into the furnace, where combustion takes place. A circulation of the air is maintained by means of a stack or chimney through which the burnt gases or products of combustion are carried off. In such an arrangement, the draft varies considerably, 20 owing to daily variations in the temperature of the outside air and also to changes in weather conditions. As the outside temperature lowers, the draft through the stack correspondingly increases, so that the gases are drawn through and beyond the melting chamber before complete combustion has taken place. On the other hand, a rise in temperature may reduce the draft to such an extent that the amount of air supplied to 30 the melting chamber is insufficient to produce complete combustion, resulting in a lowering of the temperature and waste of fuel.

Theoretically, it is possible to regulate 35 the draft by dampers in the smoke stack, but it is practically impossible to get the average workman to properly regulate such dampers. This difficulty is increased by the fact that there are different shifts of work-

40 men, usually three, every twenty-four hours, so that the regulation cannot be left in charge of any one person.

In accordance with the present invention, there is provided within the air circulating 45 system, a draft blower preferably between the furnace and the stack. This blower is run continuously at a constant speed, so that a substantially constant draft is maintained independently of atmospheric conditions, 50 thereby securing uniform combustion and heat conditions within the furnace. This

blower may be an induced draft blower operable to draw the air from the furnace and force it toward the smoke stack. In its preferred form, the invention also includes 55 a forced draft blower in the air circulating system, by which air is forced into the furnace, thereby assisting in maintaining constant and uniform conditions of combustion within the furnace.

60 A further feature of the invention relates to the arrangement whereby the air for combustion is drawn from the bridge wall or narrow confined space usually provided between the melting tank and refining tank 65 of a glass furnace. This further contributes to the general result of maintaining a substantially constant draft and temperature within the furnace, and also results in a saving of fuel, owing to the higher temperature 70 of the air at this point of intake, as compared with the outside air. Moreover, the circulation of air at this point of intake, assists in keeping down the temperature of the bridge wall.

75 Other objects of the invention will appear hereinafter.

In the accompanying drawings:

Figure 1 is a perspective view, partly diagrammatic of a glass furnace with regenerators and an air circulating system embodying the principles of my invention.

Figure 2 is a sectional view of the reversing valve.

Figure 3 is a detail view of a throttle valve.

Figure 4 is a view similar to Figure 1, but showing a modification in which a recuperator is used.

Figure 5 is a fragmentary sectional view 90 at the line V—V on Figure 4.

The furnace comprises a melting tank 10 and a refining tank 11 separated by a bridge wall 12, the latter providing a narrow space 13 between the two tanks or compartments. 95 A roof 14 extends over the entire furnace and provides a confined space 15 over the glass in the furnace, in which space the fuel gases are burned.

The air for combustion is drawn from the 100 space 13 in the bridge wall and passes upward through vertical pipes 16 which unite

2
in a single pipe 17 (Fig. 1), which extends to a forced draft blower 18 connected to an electric motor 19, which may be run continuously at a constant speed. The blower 18 forces the air through a pipe 21, past a throttle valve 22 and through a pipe 23 to a reversing valve 24. This valve directs the air to either of two conduits 25 and 26, depending on the position of the valve. With the valve in the position shown in full lines (Fig. 2) the air is directed through the conduit 25 to the checker chamber 27 of a regenerative furnace, which may be of usual construction. The air is heated in its passage through the checkerwork in the chamber 27 and then passes through conduits 28 and 29 to the interior of the furnace where it is mixed with the fuel gas and burns within the space 15. The burnt gases pass from the furnace through conduits 30 and 31 to and through the checker chamber 32. The gases in passing through this chamber, heat the checkerwork therein and then pass through the conduit 26 and past the reversing valve 24 to an exhaust conduit 33 leading to an induced draft blower 34. This blower is run continuously by an electric motor 35 at a constant speed and in a direction to draw the burnt gases through the exhaust conduit 33 and force them upwardly through the smoke stack or chimney 36. The reversing valve 24 is periodically reversed at regular intervals, thereby reversing the direction of flow through the furnace and through the checker chambers 27 and 32. Each reversal causes the fuel air to pass through the checker chamber which has been heated by the spent gases which have been passing through such chamber just prior to such reversal.

40 By drawing the air from the passage 13 in the bridge wall, which air is quite hot and is of much more nearly constant temperature than the outside air, an economy of fuel is effected. Also, a more nearly constant temperature is maintained. A circulation of air through the space 13 is also maintained, which materially assists in preventing overheating of the bridge wall.

45 Under some conditions, satisfactory results may be obtained by omitting either the induced draft blower 34 or the forced draft blower 18. The use of both blowers, however, in combination, gives more reliable and uniform results under widely varying conditions.

50 Figures 4 and 5 illustrate my invention as applied to a glass furnace having a recuperator 40, or recuperators on one or both sides of the glass furnace. The air passing through the forced draft blower 18 is forced through a pipe 41 into a chamber 42 within the recuperator 40. From thence the air is conducted through passageways 43 into the main furnace where combustion takes place.

The gases of combustion pass from the furnace through a passageway 44 back into and through the recuperator to a conduit 45 leading to the induced draft blower 34. The recuperator furnace may be of any usual or 70 approved construction and serves to heat the fuel air before it enters the furnace.

Modifications may be resorted to within the spirit and scope of my invention.

75 What is claimed is:

1. The combination of a furnace and a circulating system through which air for combustion is circulated, said furnace comprising a wall having a channel therethrough opening directly to the outside air, said circulating system having its intake at said channel, whereby fresh air enters directly from the atmosphere into said channel, is heated therein and is drawn from thence into the circulating system. 80

2. A furnace comprising a melting chamber and a refining chamber separated by a bridge wall having an air space or channel therein, and pipes leading from said channel and communicating with the interior of the 90 furnace for supplying air for combustion.

3. A furnace comprising a melting chamber and a refining chamber separated by a bridge wall having an air space or channel 95 therein, a blower, a pipe leading from said channel to the blower, and means providing a passageway leading from the blower to the interior of the furnace.

4. The combination of a furnace tank, a regenerative furnace comprising checker chambers on opposite sides of the tank and communicating with the tank, an air circulating system comprising a channel formed in the tank walls and opening directly into the atmosphere, conduits leading from said channel to said checker chambers, a reversing valve in said system by which the air is directed alternatively to said chambers, and a forced draft blower located in said air system between said valve and said channel. 100

5. The combination of a furnace tank comprising a melting chamber and a refining chamber separated by a bridge wall having an air space or channel therein, a regenerative furnace, a conduit leading from said channel to the regenerative furnace for conducting heated air to said furnace, and means for conducting the air from the said furnace to the interior of said tank. 115

6. The combination of a furnace tank comprising a melting chamber and a refining chamber separated by a bridge wall having an air space or channel therein, a regenerative furnace, a conduit leading from said channel to the regenerative furnace, a blower in said conduit, and means providing a passageway leading from the regenerative furnace to the melting chamber. 125

7. The combination of a furnace and a circulating system through which air for com- 130

bustion is circulated, said system comprising a conduit leading from a source of fresh air supply and communicating with the interior of the furnace, a forced draft blower located in said conduit and operable to draw fresh air therethrough and force it into the furnace, a conduit leading from the furnace for carrying off the spent gases of combustion, a chimney with which said last mentioned conduit communicates, and an induced draft blower located within said last mentioned

conduit and operable to draw the gases from the furnace and force them into the chimney.

Signed at Toledo, in the county of Lucas ¹⁵ and State of Ohio, this 13th day of September, 1924.
